UNITED STATES PATENT OFFICE

97,736

DESIGN FOR A CAR MOVER

Allen J. Hoffmann, West Allis, Wis.

Application April 29, 1935, Serial No. 56,611

Term of patent 14 years

To all whom it may concern:

Be it known that I, Allen J. Hoffmann, a citizen of the United States, residing at West Allis, in the county of Milwaukee and State of Wisconsin, have invented a new, original, and ornamental Design for a Car Mover, of which the following is a description, reference being had to the accompanying drawing forming part thereof.

In the drawing:

Fig. 1 is a side elevation of a car mover embodying my new design;

Fig. 2 is a full top view of the car mover; and Fig. 3 is a full bottom view of the car mover. The important feature of the present design resides in the car mover having the shoe and arch lever formed with gradually curved bounding lines, and the elimination of sharp corners.

I claim:

The ornamental design for a car mover substantially as shown and described.

ALLEN J. HOFFMANN.
